ABSTRACT OF THE DISCLOSURE

The invention provides a one-piece car-truck and coupler apparatus as used in railway equipment and has application to toy or model railroad apparatus but is not limited thereto.

FIELD OF THE INVENTION

The invention relates to the field of railway equipment, and in particular to the car-truck and coupler apparatus used on railway equipment. The invention arose in the art of model or toy railway apparatus.

Prior art car-truck and coupler arrangements are made up of several parts or pieces which are expensive to manufacture and which involve time and expense to assemble. In addition to the above, the multi-piece apparatus of the prior art causes frustrations for the model railroad builder due to the handling of a plurality of small pieces. In particular the prior art devices included small springs to provide resilient coupling members.

The present invention provides a one-piece construction which is easy to handle and inexpensive to manufacture.

SUMMARY OF THE INVENTION

In brief, the invention provides a one-piece car-truck and coupler for railway apparatus in which the car-truck and coupler are connected by a flexible web. The coupler portion includes a hook having two horizontal beveled portions which meet at a protruding edge so that when two similar couplers abut they flex so one rides over the other far enough that they flex back to their normal horizontal position engaged. The resilient web allows the hook to flex out of its normal horizontal position.

BRIEF DESCRIPTION OF THE DRAWINGS

FIG. 1 is a top view of the one-piece car-truck and coupler of the invention.

FIG. 2 is a side view of the one-piece car-truck and coupler of the invention.

FIG. 3 is an end view from the coupler portion hook.

FIG. 4 is an end view from the car-truck portion.

FIG. 5 is a bottom view of the car-truck and coupler.

FIG. 6 is a partial cross-sectional side view of the apparatus of the invention as seen from lines 6—6 of FIG. 1.

FIG. 7 is a partial cross-sectional view as seen from lines 7—7 of FIG. 1.

FIG. 8 is a side view of two coupler hooks illustrating the flexing action as the beveled portions ride on each other to accomplish the coupling action.

DESCRIPTION OF THE PREFERRED EMBODIMENT

Referring now to FIGS. 1-8 which are hereby made a part of the specification, a one-piece railway car-truck and coupler 2 is provided in which a car-truck portion 4 and a coupler portion 6 are joined by resilient web members 8 which are horizontally spaced apart in a common plane and are flexible along imaginary lines between said truck portion and said coupler portion and transverse of the path of travel of the truck. The wheels 10 are mounted

2

onto the car-truck and coupler 2 but do not form part of the one-piece construction of the invention.

The coupler portion 6 includes a hook piece 12 and beveled surfaces 14 and 16 which meet at the protruding edge 18. As illustrated in FIG. 8, when two similar car-truck and couplers 2 abut, the protruding edges 18 meet and deflect the hook and coupler members 6 and 12. Further movement of the couplers toward each other causes the resilient webs 8 to flex so that the beveled surfaces 14 and 16 ride or slide over each other to the position shown in the broken line of FIG. 1 where the two coupler hooks 12 engage. In this position the resilient webs 8 allow the couplers 6 to flex back to their normal horizontal positions.

Stop members 20, 22, 24 and 26 are provided to limit the extent of flex by the resilient web members 8. At one limit position of flex, the stop members 20 and 22 abut while at the other limit position stop members 24 and 26 abut.

In the preferred embodiment the one-piece car-truck and coupler is molded of plastic material with the web portions 8 being relatively thin to provide their resilient characteristic.

It should be noted that the webs 8 could be formed as one web rather than the two shown.

Although the preferred embodiment is directed to a toy or model railroad one-piece car-truck and coupler, the invention is intended to encompass full scale railroad equipment as well.

It should be understood that this invention is not limited to specific details of construction and arrangement thereof herein illustrated, and that changes and modifications may occur to one skilled in the art without departing from the spirit of the invention; the scope of the invention being set forth in the following claims.

What is claimed is:

1. Railway truck and coupler means comprising truck and coupler apparatus of single-piece construction, the coupler portion having a part in opposed horizontally spaced relation to a part of the truck portion, said parts being connected by at least one horizontal web portion which is resiliently flexible along imaginary horizontal lines transverse of the path of travel of said truck between said parts of the coupler portion and the truck portion, said coupler portion having a hook and flexing of said web providing for vertical movement of said hook to couple and uncouple the hook to and from a hook of a similar truck and coupler apparatus.

2. Railway truck and coupler means as defined in claim 1 wherein there are two webs horizontally spaced apart in a common horizontal plane and resiliently flexible along a common imaginary horizontal line between said parts of the coupler portion and the truck portion and transverse of the path of travel of the truck.

3. Railway truck and coupler means as defined in claim 2, wherein said hook has a beveled surface to cause the hook to move vertically when butted against said hook of a similar truck and coupler apparatus to allow the two hooks to pass each other and become coupled as they move back to their normal positions.
